APPARATUS FOR TREATING STRIP STEEL

Charles Clarke Wales, Cleveland, Ohio

Application October 20, 1937, Serial No. 170,038

2 Claims.

(Cl. 29—33)

This invention relates to apparatus for handling sheet steel, particularly in the continuous pickling of hot rolled strips. Certain principles hereof are also applicable in connection with other treating and/or fabricating operations on sheet or strip steel, for example, annealing, tempering and whatever other operations can be performed on strip steel while advanced continuously or in successive steps.

At the present time there are in operation two types of continuous strip picklers: (a) the single strand or pinch-roll-controlled type of unit, used principally for pickling scale from hot rolled strips in single strands in widths from 22" to 96", and in thicknesses from $\frac{3}{32}$ " to $\frac{1}{8}$ "—at speeds from twenty five to one hundred and seventy five feet per minute, depending upon the number of acid tanks; and (b) multiple strand type units, used principally for pickling several strips side-by-side, say from two to eight or more separate strands at a time. Type "b" is principally used in pickling strip from two inches up to twenty inches in width, and from .031" to .080" thick. The present invention relates to the handling of strip stock as in Type "a," although it enables multiple strand treatment to be effected as will later be shown.

In the multiple strand units, the prior practice has been to draw the strips off the feed reels and through the acid tanks by recoiling apparatus at the delivery end of the system; no attempt being made to level the stock, principally because such would interfere with pulling through. The trailing end of each strip is usually tied to the leading end of another as by the use of manually applied acid resisting hooks or other tying devices; and, since the stock is relatively light in weight and flexible, the workmen are able to effect tying together of the trailing and leading ends and removal of the tying devices, as necessary, without having to provide intermittently operable feeding means to assist in applying and, subsequently, removing the fastening or tying means.

Such multiple strand type (pull-through) apparatus, as far as I am aware, has never been so arranged that the feeding devices for the individual strips can operate on a single strip which in width approaches the maximum width capacity of the unit. It would seem that the pulling mechanism could be rearranged and adapted to handle strips of any width capable of entering the pickling tanks; but, in connection with pull-through systems, there are practical limitations in the way of satisfactory operation on widths and thicknesses greater than the maxima above indicated. For instance, any strip wider than 20" would be naturally unwieldy and difficult to manage, even though the stock is comparatively thin. The wider or heavier the

stock, the more difficult it becomes to tie the trailing end of one strip to the leading end of another in the manner practically necessitated by the use of a pull-through type of apparatus. Speed capacity of pull-through types is also limited by the strength of end-to-end connections between strips; for if the tank length is great enough to allow substantial increase of strip speed (must then be lengthened to maintain necessary immersion period), the connections are apt to fail. Moreover, a strip as thick as $\frac{1}{2}$ " usually develops coil breaks as it leaves the supply coil (has scallop formation as viewed edge-wise). Obviously a wide or heavy sheet that has developed coil breaks would be difficult to move over the carrier rollers, across the bottom surfaces of the tanks, and past the usual depresser rolls which assist in maintaining proper immersion, and would cause rapid wearing and strain on the equipment.

The above discussion of the usual multiple strand unit type of apparatus is in order that the present subject matter will not be confused therewith, and in order that the problems solved by the present invention (having to do principally with the handling of material which is wider or thicker than can be effectively handled on multiple strand type apparatus as heretofore used) will be more clearly understood.

With the above in view, the principal object of the present invention is to provide an apparatus which will operate efficiently to treat and feed fairly heavy gauge strip steel either in a single strand or strip, as wide as can pass through the elements of the apparatus, or (interchangeably) at least two relatively narrow non-overlapping strips of any total width under such predetermined maximum, and, specifically, to provide an improved system, apparatus and mechanism for pickling sheet steel in substantially continuous strip form.

A further specific object is to provide a sheet pickling system of the pinch-roll controlled type, which will operate efficiently, interchangeably, on wide and narrow sheets.

Another object is to provide for increasing the efficiency and operative capacity of continuous strip pickling plants, in a manner that will not require enlargement of permanent buildings now adapted for strip pickling purposes.

Another object is to provide a treating apparatus for strip steel by which the rate of progress of the stock through the necessary feeding, shearing, stitching and unstitching units and essential treatment means may be greatly speeded up, as compared to present practice.

The provision of an apparatus wherein wide and narrow sheets may be treated interchangeably at speeds comparable favorably with those now used in single purpose treating plants, (sin-

gle strip or multiple strip) or at higher speeds, requires wider spacing of operating units, as between the initial stitch control feeding and the feeding means which further advances the stock to the zone of essential treatment of the strip (such as pickling); and a further specific object is to provide such increased spacing without having to increase the size of buildings now adapted for such treatment; without reduction in scale of the necessary apparatus; without having to effect relatively expensive changes in the equipment used; and without having to provide out-buildings for accommodating any of the mechanisms included in the system. Ancillary objects, in line with the above, include the provision of an improved looping arrangement for stock between different feeding mechanisms.

Other objects and features of the invention will become apparent from the following description relating to the accompanying drawings which show the preferred arrangements and constructional features incident to carrying out the method.

Referring to the drawings, Fig. 1 is a more or less diagrammatic side elevation of the apparatus arranged for pickling hot rolled strips; Fig. 2 is a similar view, showing an alternative arrangement for the same purpose, portions of the pickling tanks in both figures, being broken away, to enable showing the entire system in single views; Fig. 3 is a plan view of the arrangement, according to Fig. 2, it being understood that, in general, a plan view of the Figure 1 arrangement would be substantially the same as a plan of Fig. 2 except that the order of placement of initial feeding and fabricating mechanisms, shown at the right, is reversed; Fig. 4 is a plan view of a pinch roll mechanism and also a portion of one of the pickling tanks and a dancer mechanism operating therein to control the speed of one set of pinch rolls; Fig. 5 is a view similar to Fig. 4, showing the effects of adjusting the pinch roll and dancer mechanism for pickling single sheets; Fig. 6 is a sectional view, through the pinch roll mechanism, as indicated by the line 6-6 on Fig. 4; and Fig. 7 is a front elevation and Fig. 8 a side elevation, respectively, of a suitable form of shearing or press mechanism, which is adaptable for cropping, stitching and unstitching.

The simpler arrangement of Fig. 1 will first be described, in general, without reference to making the various mechanisms interchangeable for use on single wide strips and two narrow strips. The arrangements are adapted specifically for pickling.

Referring to the right hand portion of Fig. 1, the coils A of stock to be pickled are delivered from a direction transverse to the direction of feeding strip through the system, as on a standard double inclined roller conveyor, shown at 1. The coils may be moved off the conveyor, as to the position A' and the free edge of the strip in feeding position is passed between the rolls of an uncoiler and leveler mechanism 2 of any known or suitable form, adapted to remove the coil breaks from the stock, level it, and advance the leading edge to a cropping shear mechanism or other cropping means indicated generally at 3. This may be arranged as an up-cut or down-cut shear, and operates to sever the irregular end (formed in the usual hot rolling process) from the strip. The strip is then passed to a stitching mechanism 4; and assuming another strip has preceded the one under discussion, the tail

end of such preceding strip is held at the stitcher until the leading end of the new strip is advanced over it to stitching position. The detailed construction of the shear 3 (or a suitable form of such) which construction may also apply in a general way to the stitcher 4, will be later described. Usually the stitcher operates by punching through portions of one strip into interlocking relation to the other, as is well known. Instead of stitching in the manner indicated, spot, line or butt welding may be used to attach the extremities of the strip together; and as used herein the term "stitching" or "stitching mechanism" includes welding, and any other way of fastening strip stock sections in end-to-end relationship.

From the stitching mechanism 4 the stock passes through a pinch roll stand 5. This is principally useful in controlling the position of the tail end of such preceding strip, as above mentioned, with reference to the stitching mechanism 4. The tail end of such preceding sheet is (or can be) cropped, as by the mechanism 3 when such tail end passes said mechanism. The strip passes from the pinch roll stand 5 over a looping space which may be in the form of a pit 6, to a second pinch roll stand 7. The loop in the stock is diagrammatically indicated at B.

A suitable construction of the pinch roll stands for interchangeable use on wide and narrow strips, will be hereinafter fully described, which construction may also apply to a final pinch roll mechanism at the delivering end of the pickling system. The controls for the two stands 5 and 7 differ in that the stand 5 is controlled manually, since the stitching and cropping ordinarily would be controlled manually, whereas the stand 7 preferably is controlled by a dancer mechanism, including a dancer roll 8, which rests on top of the strip or strips being advanced by the pinch roll stand 7 over a carrier roll 9 at the entrance to the first tank 10 in case there are a plurality of tanks.

The dancer roll, controls, as by a suitable rheostat or rheostats, the speed of operation of the stand 7, and this maintains the proper amount of sag in the tanks. The provision for the slack or loop, such as B, in the stock between the pinch roll stands 5 and 7, is in order that pickling may proceed at a uniform rate notwithstanding stoppage of portions of the strips for cropping and stitching. Temporarily, after stitching, the rolls of stand 5 are speeded up until there is a safe amount of slack between the stands 5 and 7, sufficient to avoid pulling the stock in two, or damaging the pinch stands and to avoid pickling time loss; and then, until the next cropping and stitching operations are performed the two pinch stands may be substantially synchronously driven.

The dancer roll 8 operates substantially in the usual way to control the pinch roll speed; the operation however being modified in order that either one or two sheets can pass through the system, and, in case there are two, that these can move independently of each other. As the strip tightens and tends to rise from the first tank, it raises the dancer roll, and this, in turn, speeds up the rolls of the stand 7 until the dancer roll or rolls again assumes or assume normal position, in which the strip or strips at C is or are again properly immersed in the solution contained in the tank.

The strip then passes from tank to tank over rubber covered carrier rolls 12 (only one set

shown), between adjacent end walls of adjacent tanks, finally emerging from the last tank over a rubber covered carrier roll 13. There may, of course, be any number of tanks, say from two to eight. A plurality of tanks are used partly because raising the stock periodically from the pickling solution hastens pickling, and precipitation of loosened scale from the stock.

The pickled stock, after it passes over the final carrier roll 13, is drawn, as by a pinch roll stand 15 at the delivery end of the pickling plant, through a scrubber 16, which may be of any type, and then through a drier mechanism having portions 17 and 18. The construction of the stand mechanism 15 may be same as in case of stands 5 and 7.

Preferably the scrubbing and drying is done partially mechanically as by reciprocating or rotary brushes, and partially by hot-water or steam or both, the heat applied being important in order to effect drying. Suitable air blasts may also be used; it being important that the stock be fully dried before recoiling beyond the pinch roll stand 15.

As the stitched portions of the various strips pass beyond the stand 15, the feeding operation of the rolls of the stand 15 is interrupted for a sufficient period to allow the stitched portions to be sheared out, as by a down-operating shear 20, having a double knife adapted to cut the overlapped and stitched ends of the strips simultaneously, and to discharge the severed sections out of the way. The construction of the "unstitching" shear mechanism may be the same in principle as the shear 3 and stitcher 4.

The pickled stock is finally recoiled, as in a coiling unit 21, which operates similarly to the uncoiler 2, but in a reverse direction. The stock being recoiled, is indicated at D. Such recoiling unit is preferably of the three-roll type, either up-coiling or down-coiling, although, alternatively, the stock may be taken off onto a drum-type reel. From the recoiler unit, the coil is discharged away from the pickling system, as on a conveyor 24, operating transversely of the line of progress of the strip or strips through the plant. It is common practice in recoiling to oil the strips for cold rolling or for protection when being shipped to customers, as hot rolled pickled coil.

A variation in the general arrangement above described is shown in Fig. 2. This variation, in general, refers to feeding the stock through the uncoiler, cropping shear, stitcher and first pinch roll, in a direction reverse to that of the progress of the stock through the pickling tanks. In other words, the direction of movement of the stock is reversed between the first and second pinch roll stands. The reason for this arrangement is in order to provide additional looping space, in the event of feeding two strips of stock, and therefore having to effect cropping and stitching at more frequent intervals than when running through a single strip. The various mechanisms are numbered the same as in Fig. 1, it being noted that the uncoiler, shear, stitcher and first stand, are located in a plane above the floor level, indicated at L. There is an underpass P, by which the stock can return, below the various mechanisms mentioned, to the second pinch stand 7. Alternatively, the mechanisms mentioned, i. e., 1 to 5, can be placed below the floor, and the loop then passed above said mechanisms to the stand 7.

Two methods of looping are indicated on Fig. 2.

In one arrangement (strip looping substantially according to line E) the stock is carried over a supporting roller 25, and loops in a position beyond the machinery, say outside the building and under a shed, from which position it returns through the underpass, and finally, under the guidance of rollers 26 and 27, to the pinch roll stand 1.

Alternatively, the stock may pass as in the loop formation such as F, indicated in broken lines; the stock passing over a suitable supporting roller 29, in line with the first pinch stand, and thence downwardly into a looping pit 30, preferably built as a tank, to contain water. The stock of the loop passes upwardly from the pit and over a suitable guiding roller 31 to the underpass.

Near the top of the pit, and in the region in which the loop of the stock engages the supporting roller 31, I preferably provide a baffle 32, extending clear across the pit, which holds back any scum, which may accumulate on the outer portion of the pit, wherefore, as the stock leaves the pit, it will pass out of relatively clean water and carry less foreign material with it than would otherwise be the case. Heat is maintained in the water of the pit by any suitable means. In addition to cleansing the stock, heating of it enhances the pickling process (enables faster pickling speed) without having to increase pickling tank capacity.

In readapting existing plants to use the system shown in Fig. 2, it is unnecessary to enlarge the buildings in order to obtain greatly enlarged looping space—in other words, a much greater amount of slack between the two pinch roll stands, such as 5 and 7. In case the loop extends outwardly as at E, a relatively small opening may be made in the building wall and any suitable inexpensive shed placed over the area into which the loop extends. To avoid fouling I propose to employ means to pull out the loop or loops, such as cars R, Fig. 2, on tracks inclined downwardly away from the plant proper, and having arms, rollers or bails S to engage the loops. Either such cars or the loops could be biased in the proper direction by any convenient counterweight or spring operated system. Alternatively the loops could be hoisted by counterweights on suitable tackle, right inside the plant building. In case the looping pit is used, this may be installed either in the main building or outside it under inexpensive shedding.

Referring now to the plan view of the apparatus and system shown in Fig. 3, it will be noted that there are two strips of material being treated, which strips pass through all the mechanisms comprising the system, including the two acid tanks shown in side-by-side and spaced relationship. To accomplish this, it is necessary, individually, to drive the two strips at all the pinch roll stands, and individually to operate the stitcher, cropping shear and unstitcher. The uncoiler and leveler and the recoiler rolls may also be individually driven as to the two portions of each unit which act on respective strips. I have arranged for individual treatment of narrow strips as will be described in connection with Figs. 4 to 8, and the same arrangement operates to feed, crop, stitch and shear a single strip the width of which may be as great as the combined maximum width of the two strips shown in Fig. 3, including the intervening space between such two strips.

When working a single strand pinch-roll-controlled pickler it is customary to speed up the

recoiler (as 21) after shearing out the stitching, so that the recoiling of the strip may be finished and the coil discharged away from the pickler before the on-coming coil end of the next strip reaches the recoiler. This speeding up of the recoiler is impossible in the present system when pickling two strands, and it is therefore proposed, to avoid difficulties, that the finished coil be ejected as shown in Figs. 1 to 3, toward the discharge end of the pickler, onto the conveyor 24 over a table between the shear 20 and the recoiler. Thus, it is possible to pickle material in single strands in the same manner and throughout the same width and gauge as by standard pinch-roll-controlled types of picklers, many of which are now in operation. It is also possible to pickle two strands at a time in widths slightly less than half of the maximum single strand pickling width and the production efficiency is increased to a very large extent on the narrow material.

Specific mechanisms

The general principle of operation of the various pinch roll stands is the same; additional refinements being provided to control, automatically the second pinch roll stand 1, as shown on Figs. 4 and 5. The two shearing mechanisms and stitchers all may be operated on the same general principles, which will be described in connection with Figs. 7 and 8. The specific showing of shearing mechanism of the latter figures is that of the double shear mechanism 20, for removing the stitched overlapped ends of two or more strips.

Referring now to Figs. 4, 5 and 6, the pinch roll stand shown, has heavy side frames 40, carrying upper and lower pinch rolls 41 and 42. The rolls are split in the center in case it is desired that the two narrow strips of stock to be treated interchangeably with one wide strip are of substantially equal width. However, the rolls may be split at any other point intermediate of the two frames, should it be desired to run a strip wider than half the total width capacity of the various mechanisms, together with a strip materially less than half such width.

As shown in Fig. 6, the roll sections 41a and 42a, 41b and 42b have driving shafts 45, journalled in appropriate relatively adjustable bearings 46, which may be moved toward and away from each other, to govern the driving pressure and accommodate different thicknesses of stock, as by the usual jack mechanism including screws 48 operatively bearing downwardly through suitable springs on vertically adjustable bearing blocks which carry the bearings for the upper shafts 45. The screws may be individually adjusted by hand-wheels 50, which are drivingly connected to respective screws 48 in any suitable manner.

The specific driving arrangement for the shafts 45 illustrated, comprises a housing 52 for permanently meshed gears 53, drivingly rigid with respective shafts 45, one of the gears being permanently connected to a reduced gearing mechanism 55, operated by an electric motor 56. The drive for the sections 41b and 42b, which are at the left in all figures, may be identical with the driving mechanism shown at the right in Fig. 6 and just described. Each driving mechanism has its own motor. The control for the motors may be manual or automatic, i. e. governed by the work, as in case of the dancer-controlled pinch roll stand 1.

An appropriate means for supporting the inner ends of the roll sections 41a and 41b, 42a and 42b, may comprise providing, on one of each pair of aligned sections, as 41a, a heavy pilot extension 57, having spaced bearings 58 in an axial bore 59 of the other section of such pair. One extension 57 projects to the right and one to the left, in the particular arrangement shown.

When using the system for conveying two strips, the roll sections at each side are independently driven, that is, started and stopped, speeded up or slowed down in accordance with operating conditions, requisite to the individual strips, but when feeding a single wide strip, which bridges the two roll sections, it is then practically essential that the aligned sections operate as a unit. To accomplish this, the sections may be simply pinned together at their telescoping regions, as by removable pins 60, shown only on Fig. 6. A more quickly operable connecting and disconnecting means may be provided between the sections of each roll, or at least the sections of one of the rolls; for example, a dental clutch, not shown. I also contemplate synchronizing the driving motors of the driving mechanisms on each side, so that no positive interconnection between the roll sections would be necessary to cause them to operate, in effect, as single upper and lower pinch rolls.

Referring particularly to Fig. 4, a spacer or center guide 62 is provided between the two strips of stock, in order to prevent the edges of either strip from spanning the break in the roll. This center guide may be removably supported, preferably by the pinch roll stand frame in suitable fashion, and is removed when using the system for a single wide strip. Side guides 64 for the extreme edges of the strip or strips, passing through the stand, may be adjustably mounted on appropriate guideways, and their positions adjusted by right and left-hand screws, as usual.

Figs. 4 and 5 show the dancer roll arrangement, which I propose to use at the entrance to the first acid tank, to control the speed of the pinch rolls of the stand 1. This comprises, preferably, sectional shafting extending across the tank and supported, as on its top wall. The shaft section 65 extends within the section 66, which is hollow, and the two sections 65 and 66 may be secured together as by a pin 67 or any suitable clutch arrangement (not shown). Parallel arms 68, on respective sections of the shafting, support the dancer rolls 8, heretofore mentioned. These rolls ride on the strip or strips, as the same passes or pass into the tank. When operating on two strips, the dancer rolls operate individually to turn the sections 65 and 66, which in turn, through any suitable means, govern respective controllers for the motors 56. As shown, motor field rheostats 69 are indicated diagrammatically, and the control connection, with the shafting may comprise contactor arms 70 secured to respective shaft sections 65 and 66 and adapted to contact successively with the rheostat points of respective rheostats. By this means, if two sheets are being run, the operation of the pinch rolls driving one strip is independent of the operation of the other. It would probably not be necessary to connect the shaft sections 65 and 66, together, for single sheet control, if the stock were truly uniform transversely of it. When this is not the case, I provide for connecting the dancer roll frames to insure their unitary operation on a single sheet,

irrespective of transverse non-uniformities of stock.

It will be understood that in the case of the first pinch roll stand 5 this is not provided with any arrangement similar to the dancer roll hook-up described, but there the motors are controlled either individually or together, as by the workman in charge of cropping and stitching; independent or single control being used in connection with running two sheets and one sheet, respectively, as will be obvious from the above description.

The shearing unit (for instance unstitching unit 20) which is shown in Figs. 7 and 8, represents a known type of mechanism, wherein the shear blades are appropriately split and usable individually or together, for multiple-strip and single-strip fabricating, respectively. If the endwise adjacent strips are to be interlocked together, to stitch them, then the same general design of machine can be used for stitching, simply by changing the tools from shear blades to stitching dies of known or suitable form.

In Fig. 7 the general framework of the machine is indicated at 75, the main power shaft 76 being appropriately journaled on the frame sides, and controlled manually in a well known manner by a single rotation clutch mechanism 76a. The shaft 76 has crank portions operating to reciprocate connecting rods 77, one being shown on each side of the machine in Fig. 7. The rods, in turn, reciprocate the upper part 78 of a sectional crosshead, slidably mounted on appropriate guides at opposite sides of the frame. Two sets of movable shear blades 80 and 81, are supported individually by lower crosshead sections 79 spaced from the upper sections and normally out of the range of movement of said upper sections. The lower blades 82 may be fixed and each made as single sections or in as many sections as desired.

In the arrangement shown, the power shaft 76 turns once to effect cutting of strip stock by the blades, and either blade 80 or 81 may be lowered to effect cutting, or both may be lowered together. The selective operation is under the control of lever arms 85 and 86, which are operatively associated with the blade sets 80 and 81, respectively, through telescoping shafting. The sections of the shafting are indicated at 87 and 88, and these are turned by the arms 85 and 86. When the arms are turned in a clockwise direction (as viewed in Fig. 8), they operate through upstanding arms 89 (normally held out by springs) to move sliding blocks 90 between the upper and lower sections 78 and 79 of the crossheads, above referred to.

It will be seen that if the blocks or crosshead interponents 90 of one set are moved between the crosshead sections and the shaft 76 given its single rotation, then only the respective side of the shear operates to cut, and if the blocks of both sets are moved in, then both sides of the shear operate. Thus the workmen can effectively crop or stitch or unstitch single strips passed through the system, and, just as effectively perform such fabricating operations individually on strips in either of two lines (narrow strips as described) as the ends reach the fabricating positions, but without having to interrupt progress of the strip stock in the other line.

Any form of control, other than shown, can be used for the selective fabricating mechanism, either for cropping, stitching or unstitching, as

above pointed out. The mechanism of Figs. 7 and 8 may be driven by an electric motor 100, connected to the power shaft 76 in a manner which it is unnecessary to describe in view of such mechanism being well known in the art.

Having in mind that, in order effectively to treat sheet strip stock of such gauge as to require stitching of ends, as against merely hooking the ends together, and to require leveling, a pinch-roll-controlled type system is necessary, it will be clear from the above description that greatly increased efficiency can be obtained by the use of the system herein disclosed when required to run stock in widths less than 50% of the width capacity of the various mechanisms. The usual strip treatment plant of the class shown can be somewhat speeded up when running such narrow strips, but such speeding up usually results in inferior work because, as in pickling, the stock has to remain in the acid a certain time. An increase in tank capacity for the sake of speeding up in case of running narrow strips would obviously result in decreased efficiency when having to run wide sheets. By the system and mechanism hereof, narrow strips of such gauge as to necessitate pinch-roll-controlled units to run them, can be treated, without requiring disproportionate investment in additional equipment, at efficiencies comparable favorably with those which obtain in case of running single strips of widths which nearly equal the capacity of the apparatus. It will also be seen that by the rearrangement of instrumentalities herein disclosed there can be obtained greatly increased output without requiring expensive building enlargements over the present practice; without sacrifice of the quality of work done; without increased hazards to the workmen; and without danger of damaging the equipment or work. Various other specific objects hereinbefore set forth have also been accomplished by the present method, system and mechanisms, as will be clear from the above description.

I claim:

1. In a treating apparatus for strip steel, the arrangement of pinch roll mechanism, a stitching mechanism and a shearing mechanism, the latter being adapted for removing stitched portions of the strip; wherein respective side portions of said mechanisms are operable independently of each other in a manner to effect independent feeding, stitching and unstitching of a plurality of individual strips in side-by-side relationship, and, selectively, simultaneously to effect the same operations on a single strip which is sufficiently wide to require that both side portions of each of the mechanisms operate unitarily.

2. In a pickling apparatus for strip steel, the arrangement of pinch roll mechanisms at opposite ends of the pickling tanks, cropping mechanism, a stitching mechanism, and a shearing mechanism, the latter being adapted for unstitching; wherein respective side portions of said mechanisms are operable intermittently independently of each other in a manner to effect independent feeding, cropping, stitching and unstitching of a plurality of individual strips, and, selectively, are operable unitarily and intermittently to effect such operations on a single strip which spans the two portions of each mechanism.

CHARLES CLARKE WALES.
